SHOE TREE

Filed July 2, 1929

BY

INVENTOR
Stefano Battilani,
Geo. Asenio
HIS ATTORNEY.

UNITED STATES PATENT OFFICE

STEFANO BATTILANI, OF NEW YORK, N. Y.

SHOE TREE

Application filed July 2, 1929. Serial No. 375,484.

The invention relates to shoe trees and has for its object to produce a shoe tree which is exceedingly simple in construction and economical to manufacture.

5 Another object of the invention is to produce a shoe tree which has sufficient resiliency to cause it to conform with the inner contour of the shoe but will not allow of distortion or stretching of the shoe.

10 Further objects and advantages will become apparent as this specification proceeds. Referring to the drawings forming a part thereof and in which preferred embodiments of the invention are illustrated:

15 Fig. 1 is a longitudinal sectional view of the shoe tree showing it in position in a shoe, the shoe being indicated in broken lines;

Fig. 2 is a sectional plan view taken on line 2—2 of Fig. 1;

20 Fig. 3 is a cross sectional view taken on line 3—3 of Fig. 2; and

Fig. 4 is a cross sectional view of a modified form.

Fig. 5 is a plan view of another modification.

Referring again to the drawings the reference numeral 5 designates the flexible arched toe piece. This member may be formed of any desirable material. As illustrated in 30 Figs. 1, 2 and 3 of the drawings, the upper portion 6 of the toe piece is arched so as to conform with the upper forward portion of the shoe. The rear edge of this portion may be turned in as indicated at 9 so as to eliminate any possibility of this edge catching on 35 the shoe lining when the shoe tree is being withdrawn from the shoe.

The lower portion 7 of the toe piece is so formed as to impart a gentle upward pressure to the portion 6 and thus cause the toe piece to snugly conform with the inner contour of the shoe. As illustrated in Figs. 1, 2 and 3 the lower portion 6 is provided with rounding sides 10, merging into somewhat 45 flattened portions 11 which are adapted to rest on the sole of the shoe. The flattened portions 11 are connected together by an arch 12. When the shoe tree is entered into the shoe the sides will be somewhat compressed. 50 This compression will be taken up by the

arch 12 and cause the flattened parts 11 to bow somewhat and raise the upper part of the toe piece so as to press it against the upper part of the shoe. While the rounded edges 10 are considered desirable they are not essential as this bend or curve may be of any suitable degree to accomplish the desired result. If desired the arch 12 might be extended outwardly or in the opposite direction to that indicated in Figs. 1, 2 and 3. The lower portion of the toe piece is provided with an aperture 13 to give more resiliency and flexibility. This opening 13 may be of any desired shape or size. The rear edges of the portion 6 may be turned in as indicated at 6a to prevent contact with the sole of the shoe when withdrawing the shoe tree.

As illustrated the toe piece is formed of one piece of material. If desired the upper and lower portions might be formed of separate pieces of material suitably joined together or under certain conditions it might be desirable to form the toe piece of more than two pieces of material.

The toe piece is provided with a rearwardly extending flexible member 14, the end of which may have a knob or suitable part 15 to engage the rear part of the shoe and hold the toe piece in position. The member 14 may be of any desired form or shape and it may be secured to the toe piece in numerous different ways.

As illustrated in Figs. 1, 2 and the means for securing the member 14 in position comprises a yoke having its sides 16 cemented or otherwise secured to the toe piece. The member 14 is mounted on the end 17 of the yoke. This yoke may be formed of a piece of spring steel wire surrounded by sleeves of celluloid or other suitable material. The form of this member may be widely varied.

The yoke may also function as a means for expanding the toe piece laterally so as to insure its fitting the shoe more snugly.

In the form illustrated in Fig. 4 bent over flaps 20 are utilized to impart the desired upward pressure to the toe piece. The rearwardly extending member 14a may be suitably secured at 21 in the forward part of the toe piece.

In the form illustrated in Fig. 5 the rearwardly extending member 25 in addition to holding the toe piece in position may help to retain the sides and heel portions of the shoe in shape. The member 25 is made of spring material and will be confined from excessive expansion by the loop 26. If desired the loop 26 may be omitted. When a large amount of expansion is desired the loop 26 may be slid 10 toward the forward part of the shoe. The member 25 is pivoted at 27 in any suitable manner to the forward portion of the toe piece.

If desired the toe piece 6 or its side portions might extend considerably further toward the rear of the shoe or for certain types of shoes it might be considerably shorter than illustrated in the drawings. Other modifications would suggest themselves to one skilled in the art and are to be considered as coming within the spirit of invention as set forth in the appended claims.

I claim:

1. A shoe tree comprising, a toe piece, the upper portion of said toe piece being arched to conform with the upper portion of the shoe and the lower portion having portions bearing on the sole of the shoe and connected by an arch so as to impart a gentle upward pressure to said upper portion.

2. A shoe tree comprising, a toe piece, the upper portion of said piece being arched to conform with the upper portion of the shoe and the lower portion having portions bearing on the sole of the shoe and connected by an arch so as to impart a gentle upward pressure to said upper portion, and a rearwardly extending flexible member.

3. A shoe tree comprising, a toe piece, the upper portion of said toe piece being arched to conform with the upper portion of the shoe and the lower portion having an aperture or cutaway part and flattened portions connected by an arch so as to bear against the sole of the shoe and impart a gentle upward pressure to said upper portion, and a rearwardly extending flexible member.

4. A shoe tree comprising a toe piece, the upper portion of said toe piece being arched to conform with the upper portion of the shoe and the lower portion have portions bearing on the sole of the shoe and connected by an arch so as to impart a gentle upward pressure to said upper portion, a rearwardly extending flexible member and a yoke composed of spring material and having its sides secured to the toe piece so as to impart an outward lateral pressure to said toe piece.

In testimony whereof, I affix my signature.

STEFANO BATTILANI.
